UNDER REAMING DEVICE

Edgar L. Carpenter, Wichita Falls, Tex.

Application January 20, 1951, Serial No. 207,018

9 Claims. (Cl. 255—19)

1

This invention relates to improvements in under reaming devices for under reaming holes for foundations thereby enabling the footings or any intermediate point of the hole to be enlarged materially so as to provide a greater bearing area when filled with concrete or the like.

Various under reamers have been proposed heretofore, but these for the most part have been cumbersome in construction and use, which has precluded their acceptance in the construction field where such a device would have the widest use.

The present device may be used in conjunction with a regulation power hole digger, and may be used to enlarge the hole at the bottom thereof or at any intermediate point, at the will of the operator. The device may be so arranged as to automatically feed the cutters outward in proportion to the revolutions of the rotary table or the cutters may be expanded outward manually to give the desired degree of expansion, up to the maximum capacity. The device may be provided with removable cutter teeth which teeth may be hard surfaced if desired, to make the under reamer adaptable for use on many types of earth formation.

An object of this invention is to provide an under reaming device the cutters of which may be manually adjusted while the device is being operated.

Another object of this invention is to provide an under reaming device that may be positioned within a hole and expanded to the desired degree so as to cut an enlargement at the bottom of the hole or at any intermediate point between the top and bottom thereof.

Still another object of the invention is to provide an under reaming device which is automatically expandable in accordance with the rotation of the rotary table.

Yet another object of the invention is to provide an under reaming device having expandible cutting elements with removable toothed sections.

A still further object of the invention is to provide a device the rotary table of which may be readily removed to permit the withdrawal of the expandible cutter elements through the opening formed by the removal of the rotary table.

Still another object of this invention is to provide a self contained under reaming unit that provides driving, lifting and expanding mechanism for the operation of the unit.

An embodiment of this invention is illustrated in the accompanying drawings, in which:

Fig. 1 is a side elevational view of the device

2

with parts broken away and shortened and showing diagrammatic representation in section of the manner of operation;

Fig. 2 is a fragmentary vertical sectional view through the rotary table with parts shown in elevation to show the construction of the rotary table and associated parts;

Fig. 3 is an enlarged fragmentary view with parts broken away and shown in section of the automatic under reaming expander feed control;

Fig. 4 is a perspective view showing the under reamer and the rotary drive table and associated mechanism together with the drill stem;

Fig. 5 is a horizontal sectional view taken above the under reamer cutters and looking downward, with parts broken away and shown in section to show the details of construction and showing the under reamer cutters in expanded position;

Fig. 6 is a fragmentary top plan view of a portion of the rotary table and associated feed mechanism and showing the drill stem in section; and

Fig. 7 is a fragmentary sectional view through the removable cutter portion of the under reamer showing the attachment of the under reamer blades.

With more detailed reference to the drawing, the numeral 1 designates a vehicle for the transportation of the under reaming device from place to place. The entire under reamer unit, generally designated at 2, is mounted on a frame 3 comprising a power unit 4, a clutch mechanism 5, transmission 6 out of which extends a drive shaft 7. A bevel gear 8 is positioned on the end of drive shaft 7 and meshes with a complementary bevel ring gear 9 which forms a rotary table, as will best be seen in Figs. 1 and 2, and 4. The rotary table is journaled on a bearing 10 and has removable spaced hold-down lugs 11 at spaced intervals around the periphery of the rotary table in overlapping relation so as to keep the rotary table in place, yet allow the rotary table to be readily removed when necessary to remove the expandible reamer, as will be more fully described hereinafter.

The rotary table, generally designated by the numeral 12, has a squared axial opening 13 therethrough which opening slidably receives a drill stem 14. A boom or derrick 15 is supported on frame 3 so as to position a sheave 16 over the rotary table in such manner that a cable 17 will align substantially with the center of the axial opening 13 therein. A swivel member 18 interconnects drill stem 14 with cable 17 to permit turning action of the drill stem 14 by rotary table 12 without twisting the cable 17. The cable 17

may be spooled on a hoist 19 and payed out a given amount to lower the under reaming element 20 into a bore hole 21 to perform the under reaming operation, such as shown at 22 and 22a in Fig. 1.

The under reamer, generally designated at 20, is mounted on the lower end of the squared drill stem 14 with the drill stem being secured to the circular bottom plate 23 and cross bar 24 so as to impart a driving relation to the under reamer elements 25, which elements are pivoted on a shaft 26 at one end for swinging movement and are held in adjusted relation by a rope or cable 27 anchored to loop 28 with the other end of the rope being wound around axle 29, which enables the cutter elements 25 to be held in any fixed relation or to be adjusted either outward or inward, either by manipulation of crank 30 that rotates a sprocket 31 or by actuation of an automatic feed.

A pair of squared shafts 32 extend upward through bushings 33 in rotary table 12, which bushings have sprockets 34 on the respective ends thereof around which sprockets a chain 35 passes and which chain also passes around sprocket 31 so, upon the turning of sprocket 31 coordinated movement is imparted to under reamer elements 25 to permit these to be moved outward or to enable these under reamer elements to be forcibly retracted.

The under reamer elements 25 carry removable cutter blades 36 which blades preferably have serrated edges. The cutter blades 36 are bolted to the outer ends of the under reamer elements 25 by bolts 37. These bolts are preferably recessed as indicated in Fig. 7, to prevent wear on the bolts and impingement of material against the bolts. When the under reamer elements 25 are fully retracted, as indicated in Fig. 1, they may easily pass into the shaft or hole indicated at 21 and be either manually expanded outward by crank 30 or permitted to expand outward upon rotation of the rotary table as will be more fully described hereinafter.

As pointed out above, the squared shafts extend upward through rotary table 12 and are slidable in bushings 33, which bushings are rotatable and journaled within rotary table 12 and fixed against longitudinal movement by set collar 33a held in place by a set screw as shown in Fig. 2.

The sprocket 34 is made integral with bushing 33 and is removable with rotary table 12 as a composite unit including chain 35 and sprocket 31, by loosening of bolts 11a which enables the swinging of lugs 11 to one side to permit the lifting of the rotary table 12 from bearings 10 either upon the removal of bevel gear 8 or the bearing member 7a.

In certain types of earth formation or strata, the cutter elements 25 may be fed outward at a predetermined rate in accordance with the revolutions of the rotary table 12. To do this, a cam actuating bar 38 is moved inward as indicated in full outline in Fig. 6, until the bar extends over a circular path defined by cam 39, which cam is mounted on a pawl 40, which pawl is pivotally mounted on a bolt 40a by a pair of upstanding lugs 40b, which lugs are attached to the upper face of the rotary table 12.

The cam 39 is adjustable on the angular face of the heel of pawl 40 as is indicated in Fig. 3, so as to vary the amount of the depression of the pawl and the length of time of engagement thereof with the cam bar 38, and the pawl 40 is forced into engagement with ratchet wheel 41 by a spring 42 mounted under the heel of the pawl 40. Upon rotation of under reamer element 20,

the blades 36 are so positioned as to dig into the wall of the hole and urge the cutter elements 25 outward, but the outward movement is restrained by means of a rope or cable 27 which is wound around shaft 29. The upstanding squared shafts 32 are restrained against movement by engagement of pawl 40 with ratchet wheel 41 formed on the upper face of sprocket 31 as will best be seen in Figs. 3 and 6. However, upon lifting of pawl 40, either manually or by the action of cam 39 engaging cam bar 38 upon circular movement of the rotary table thereunder, the cam will depress the heel of pawl 40 allowing the under reamer elements 25 to swing outward, but if the cam is only in slight engagement with the cam actuating bar 38, only one tooth of the ratchet will pass under the pawl, but, if adjusted at a higher degree on the inclined heel of the pawl 40, the pawl will be depressed a greater length of time to enable two or more ratchet teeth 41 to pass under the pawl 40 before the pawl engages with the ratchet wheel 41. The ratchet wheel 41 and integral sprocket 31 are journaled on upstanding shaft 43 that extends upward from below the rotary table 12. It is preferable to have the upstanding squared axial portion 43 made integral with the ratchet wheel 41 and sprocket 31 to enable the use of a crank 30 for the manual operation of the under reamer elements 25. The sprocket 31 carries a pointer 44 below the chain 35 which pointer is adapted to pass over indicia marked on the upper face of the rotary table, which indicia may be graduated to show the number of inches the under reamer elements are expanded.

Operation

In preparing footings for certain foundations, it is often desirable to under ream these footings so as to present a much larger bottom surface within the foundation hole, or it may be desirable to present a larger surface at some intermediate place within the foundation hole, or in other types of construction it may be desirable to under ream a shaft or hole at some particular point without the necessity of weight having to be applied to the drill stem, as has been the case with under reamers in use heretofore.

To under ream a footing either at the bottom or at any point thereabove, the under reamer, generally designated at 20, is lowered by hoist 19 and cable 17 until properly positioned. At this point the crank 30 may be manipulated so as to enable squared shafts which are in geared relation with sprocket 31 to be rotated until the pointer 44 indicates the desired number of inches, as shown in Fig. 6, at which the under reaming or cutting is to start. Then, by the manipulation of crank 30 and pawl 40, cable 27 is payed out of shaft 29 in a gauged amount to permit the under reamer elements 25 to swing outward, as illustrated in Figs. 4 and 5. Although, if desired, the cam actuating bar 38 may be moved inward so that upon rotation of the rotary table 12, by means of power unit 4, the cam 39 will pass under cam actuating bar 38 to lift pawl 40 for a predetermined time so that ratchet wheel 41 will rotate one or more notches to pay out cable 27 at a uniform rate for each revolution of the rotary table 12. As explained above, the rotary table 12 is driven by pinion 8 in mesh with ring gear 9. As the rotary table 12 is rotated, the drill stem 14 is suspended by swivel 18 and cable 17 so as to maintain the under reamer at the desired position until the complete under reaming operation is performed.

As the earth is removed from the side walls of the bore hole 21, the cutter elements 25 receive the loose dirt thereinto until the cutter elements are approximately filled, at which time the under reamer elements 25 are retracted by manipulation of crank 39, after which the drill stem 14 is lifted upward by cable 17 and hoist 19 to a position as shown in Fig. 1, whereupon, the under reamer elements may be opened to the position as shown in Fig. 5, and the earth formation therein removed either manually or by the rotary table being reversed and the earth slung out by centrifugal force. As soon as the earth is removed the cutter elements 25 are retracted and the under reamer lowered into the hole and the operation repeated until the desired results are obtained.

It is to be pointed out that a circular plate 23 is positioned below the cutter elements 25 to give additional support to the cutter elements and also to form a table on which part of the loose earth formation may rest until the tool is withdrawn and cleaned.

To operate the device without the automatic feed feature, of the cam actuating bar 38 and cam 39, the bar 38 may be retracted as indicated in dashed outline in Fig. 6, and held in this retracted position by a set screw 45, screw threaded into bracket 46, which bracket is attached to the frame member 3 exterior of the rotary table 12.

It is to be further pointed out that the cutting element or serrated blade 36 is easily removable for replacement or resurfacing with hard material as desired.

Having thus described the invention, what is claimed is:

1. In an earth under reamer the combination of an under reamer stem, a pair of longitudinal, spaced supports secured to said stem near the lower end thereof, a pair of hollow under reamer buckets each of which has an arcuate side wall, a top plate and a bottom plate secured to the respective upper and lower extremities of said side walls, each of said buckets being pivotally mounted at one end between said support members, a blade member on the respective ends of said hollow buckets opposite the pivoted ends, said buckets being arranged in opposed relation, means for limiting the outward movement of said bucket members, and means remote from said buckets for moving said buckets inward.

2. In an earth under reamer the combination of an under reamer stem, a pair of longitudinal, spaced supports secured to said stem near the lower end thereof, a pair of hollow under reamer buckets each of which has an arcuate side wall, a top plate and a bottom plate secured to the respective upper and lower extremities of said side walls, each of said buckets being pivotally mounted at one end between said support members, a blade member on the respective ends of said hollow buckets opposite the pivoted ends, said buckets being arranged in opposed relation, means for limiting the outward movement of said bucket members a gauged amount, and means remote from said buckets for moving said buckets inward.

3. In an earth under reamer the combination of an under reamer stem, a pair of longitudinal, spaced supports secured to said stem near the lower end thereof, a pair of hollow under reamer buckets each of which has an arcuate side wall, a top plate and a bottom plate secured to the respective upper and lower extremities of said side walls, each of said buckets being pivotally

mounted at one end between said support members, a blade member on the respective ends of said hollow buckets opposite the pivoted ends, said bucket members being arranged in opposed relation, means for limiting the outward movement of said bucket members a gauged amount, indicia means connected with said buckets for determining the position of said buckets when in operative position, and means remote from said buckets for moving said buckets inward.

4. In an earth under reamer the combination of an under reamer stem, a disc secured at the lower end of said stem and forming a support, a second support spaced upward on said stem and secured thereto, a pair of hollow under reamer buckets each of which has an arcuate side wall, a top plate and a bottom plate secured to the respective upper and lower extremities of said side walls, each of said buckets being pivotally mounted at one end between said support members, a blade on the respective ends of said hollow buckets opposite the pivoted ends, said bucket members being arranged in opposed relation, means for limiting the outward movement of said bucket members a gauged amount, and means remote from said buckets for moving said buckets inward.

5. In an earth under reaming device a base, a rotary table mounted on said base for rotation relative thereto, power means for driving said rotary table, gearing for connecting said rotary table with said driving means for rotating said rotary table, an aperture formed axially of said rotary table to slidably receive a stem, said stem being mounted in said aperture for unitary rotary movement with said rotary table, means connected to said stem for lowering said stem, a pair of spaced longitudinal supports secured to said stem near the lower end thereof, a pair of shafts each of which is journaled in said spaced longitudinal supports near the outer ends thereof and extending upwardly parallel with said stem and through apertures formed in said rotary table, gear means positioned on each of said shafts and slideable with respect thereto and rotatable therewith, and feed means on said rotary table for rotating said parallel shafts to move said buckets outward a predetermined amount upon the rotation of said rotary table, a pair of hollow under reamer buckets each of which has arcuate side walls, a top plate and a bottom plate secured to the respective upper and lower extremities of said side walls, each of said buckets being secured to each shaft, each shaft being pivotally mounted between said support members, a blade member on the respective ends of said hollow buckets opposite the pivoted ends, said buckets being arranged in opposed relation, means for limiting the outward movement of said bucket members, and means remote from said buckets for moving said buckets inward.

6. In an earth under reamer the combination of an under reamer stem, a pair of spaced longitudinal supports secured to said stem near the lower end thereof, a pair of hollow under reamer buckets each of which has an arcuate side wall, a top plate and a bottom plate secured to the respective upper and lower extremities of said side walls, each of said buckets being pivotally mounted at one end between said support members, a blade member on the respective ends of said hollow buckets opposite the pivoted ends, said bucket members being arranged in opposed relation, a pair of shafts each of which is journaled in said spaced supports near the outer ends thereof and

extending upwardly substantially parallel with said stem, means for operatively rotating each of said parallel shafts, means connected with each of said shafts for operatively moving the respective buckets, and means for holding said shafts in adjusted position.

7. In an earth under reamer the combination of an under reamer stem, a pair of longitudinal, spaced supports secured to said stem near the lower end thereof, a pair of hollow under reamer buckets each of which has an arcuate side wall, a top plate and a bottom plate secured to the respective upper and lower extremities of said side walls, each of said buckets being pivotally mounted at one end between said supports, a blade member on the respective ends of said hollow buckets opposite the pivoted ends, said bucket members being arranged in opposed relation, a pair of shafts journaled in said spaced supports near the outer ends thereof and extending upwardly substantially parallel with said stem, a sprocket mounted on each of said shafts in driving relation thereto and relatively slidably therein, a chain encircling said sprockets on said shafts and also encircling a drive sprocket, means for rotating said drive sprocket to simultaneously rotate said parallel shafts, means for holding said drive sprocket in an adjusted position and cable means connected with each of said shafts and to the outer end of each of said buckets to adjust said buckets in direct relation to the rotation of said shafts.

8. In an earth under reaming device a base, a rotary table mounted on said base for rotation relative thereto, power means for driving said rotary table, gearing for connecting said rotary table and said power means for rotating said rotary table, an aperture formed axially of said rotary table to slidably receive a stem, said stem being mounted in said aperture for unitary rotary movement with said rotary table, means connected to said stem for lowering said stem, a pair of spaced, longitudinal supports secured to said stem near the lower end thereof, a pair of hollow under reamer buckets each of which is pivotally mounted at one end between said support members, a blade member on the respective ends of said hollow buckets opposite the pivoted ends,

5

10

15

said buckets being arranged in opposed relation, a pair of shafts each of which is journaled in said spaced supports and extending upwardly substantially parallel with said stem, a sprocket on each of said shafts which sprockets are journaled on said rotary table and slidably relative to said shafts and rotatable therewith, a further sprocket journaled on said rotary table and having a ratchet formed thereon, a chain passing around said sprockets so as to operatively connect said sprockets on said shafts with said sprocket on said rotary table, a pawl cooperating with said ratchet for releasing said sprocket having a ratchet formed thereon for rotation of said sprocket a predetermined amount, cam means for actuating said pawl in timed relation with the rotation of said rotary table, and means connected with each of said shafts and each of said buckets to adjust each of said buckets in direct relation to the rotation of said shafts.

9. In an earth under reamer the combination of an under reamer stem, a pair of spaced, longitudinal supports secured to said stem near the lower end thereof, a pair of hollow, semi-oval under reamer buckets each of which has an arcuate side wall, a top plate and a bottom plate secured to the respective upper and lower extremities of said side walls, each of said buckets being pivotally mounted at one end between said support members, a blade on the respective ends of said hollow, semi-oval under reamer buckets opposite the pivoted ends, said bucket members being arranged in opposed relation, means for limiting the outward movement of said bucket members, and means remote from said buckets for moving said buckets inward.
